PREFABRICATED BUILDING STRUCTURE

Ernest J. Kump, Jr., Atherton, Calif.

Application December 27, 1943, Serial No. 515,761

10 Claims. (Cl. 20—2)

1

This invention relates to prefabricated buildings or to a building of the type in which the basic elements, such as the floor, walls and roof, are pre-made ready for assembly without requiring measuring, sawing, nailing, bolting, etc., as in the case where said elements are fabricated and assembled in the field. Prefabricated buildings have variously been called "demountable," "knock-down," "portable," and other terms, and insofar as this invention is concerned, any of these terms might be used, inasmuch as the structure herein described provides for rapid assembly and disassembly of the floor, walls and roof with equal facility and without mutilation thereof.

One of the objects of this invention is an improved structure in a prefabricated building whereby the floor, walls and roof may be more quickly set up and secured together by unskilled labor and by fewer workmen than heretofore, and which assembly in completed form is more complete and neater than other buildings of the same general class.

Another object of the invention is the provision of a special structure in which double-walled, relatively light panels are provided, each of which forms an inner and outer side wall and inner and outer roof structure, and each panel structurally cooperates with a floor for being pivoted or swung into its final position without requiring bodily lifting thereof or laborious fitting of intricate parts.

Another object of the invention is the provision of a prefabricated building in which one pair of spaced rows of detachably connected panels provides a gable roof and opposed side walls of the building, and which panels in one row cooperate with the panels in the other row for their proper support and distribution of the strains and stresses. Furthermore the panels of said rows are constructed of relatively light weight cores enclosed between covering sheets in which the covering sheets take the major strains and stresses instead of the cores, thereby eliminating unnecessary weight while having even greater strength than where reliance is placed on studing, rafters, trusses, etc. for taking the stresses and strains of side walls and roof.

A still further object of the invention is the provision of structure in a prefabricated building providing better heat and sound insulation than heretofore without adding anything to the time required for assembling the building.

Other objects and advantages will appear in the description and drawings annexed hereto.

In the drawings,

2

Fig. 1 is a semi-perspective view (partly in section) showing a portion of an assembled building that is illustrative of the invention.

Fig. 2 is an enlarged fragmentary perspective view of one of the panels that forms part of one side wall and part of the roof of a building.

Fig. 3 is a fragmentary perspective view of the inner corner piece of the panel of Fig. 2.

Fig. 4 is a fragmentary perspective view of the outer corner piece of the panel of Fig. 2.

Fig. 5 is a fragmentary side elevational view of the eave or angle portion of a panel that differs slightly from the panel of Fig. 2, although the core ribs and outer corner piece are identical with those shown in Figs. 2 and 4.

Fig. 6 is a fragmentary perspective view of the core ribs and inner corner piece of the panel of Fig. 5 in assembled relation.

Fig. 7 is an enlarged fragmentary perspective view of one end of a channel strip used for fastening panels together, particularly the roof sections of the panels of Fig. 2.

Fig. 8 is an enlarged sectional view taken along line 8—8 of Fig. 1.

Fig. 9 is an enlarged sectional view taken along line 9—9 of Fig. 1.

Fig. 10 is an enlarged sectional view taken along line 10—10 of Fig. 1.

Fig. 11 is an enlarged sectional view taken along line 11—11 of Fig. 1, but with the central portions of the ridge pieces omitted.

Fig. 12 is an enlarged sectional view taken along line 12—12 of Fig. 1.

Fig. 13 is a fragmentary perspective view of the ridge piece and part of the roof section of one panel that is of sound-proofing construction.

Fig. 14 is a fragmentary perspective view of a base member of the side wall section of a panel showing part of the section.

Fig. 15 is a fragmentary perspective view of part of a floor panel that is heat insulated.

Fig. 16 is a fragmentary perspective view of part of an end wall panel and side wall panel at their juncture, and which panels are sound insulated as well as heat insulated.

Fig. 17 is a fragmentary perspective view of part of the roof section of a panel and part of an end wall panel at their juncture, both panels being sound and heat insulated.

Fig. 18 is a fragmentary end view of the ridge pieces on the roof sections, said pieces being spaced apart.

Fig. 19 is an elevational view of the outer exposed side of one of the ridge pieces.

Fig. 20 is a fragmentary view, partly in sec-

tion and partly in elevation showing one structure for connecting the channel strips that are employed for securing the roof sections and side wall sections respectively of a pair of adjoining panels.

In detail, referring to Fig. 1, the basic elements shown therein comprise floor panels 1, side and roof panels 2, and end panels 3. These are generally indicated, inasmuch as they will be individually described more in detail later on, it being pertinent to point out at this time, however, that the side wall and roof panels are each of unitary structure each comprising a roof section 4 and a side wall section 5, the former being shown as extending half the width of the building from eave to ridge, while the latter extends from eave to floor.

Roof and side wall panels

The structure of one of these panels is best seen in Figs. 1 to 4 and 8 to 10. Figs. 5, 6 show slightly modified structure. The means for securing adjacent panels together is omitted from Figs. 1 to 4 for clarity, but is shown in Figs. 8 to 10.

Each panel 3 has a core or frame that comprises a row of parallel ribs 6. These ribs extend from a ridge piece 1 to a base member 8. The ridge piece 1 is cross grooved at 9 (Fig. 13) to receive one of the ends of said ribs, while the base member 8 is cross grooved at 10 (Fig. 14) to receive the opposite ends of said ribs. These grooves 9, 10 also function to facilitate quick and accurate spacing of the opposite ends of the ribs.

Ribs 6 may be constructed substantially along the lines described in my co-pending application for United States Letters Patent No. 495,425, filed July 20, 1943, Patent No. 2,413,145 granted Dec. 24, 1946, if desired, but inasmuch as the major stress strain forces in the present structure is not imposed on the ribs, the latter may each comprise a leg portion 12 and a roof portion 13 in continuation thereof, the two extending at an angle to each other so that when the legs 12 are vertical the portions 13 extend slantingly upwardly but generally horizontally, as seen in Fig. 1. The roof and leg portions may be glued together at their juncture along line 14, this juncture being at the eave part of the roof.

An inner corner strip 15 that is cross grooved at 16 for receiving similar inner edges of portions 12, 13 at their adjoining ends, spaces the ribs at the angle produced at the juncture of portions 12, 13 and an outer corner piece 17 cross grooved at 19 for also receiving the portions 12, 13 is spaced outwardly of the strip 15 but is parallel thereto. The outer corners of ribs 6 at the junctures of portions 12, 13 of said ribs are preferably cut off at an angle to provide straight edges 18 that fit in grooves 19 of piece 17. Piece 17 is triangular in cross sectional contour with grooves 19 in one side, and the other two sides respectively, transversely of the piece, are continuations of the outer longitudinal edges of the leg portions and roof portions of each rib 6.

The corner strip 15 is also generally triangular in cross sectional contour and as it constitutes the inner corner inside the angle formed by portions 12, 13, the grooves 16 are in two of the adjacent sides while the third side 20 is concavely curved transversely of the strip. The concavely curved side 20 faces inwardly and downwardly away from the inside of the angle formed by portions 12, 13 of ribs 6.

The end grooves 16 in corner strip 15 and 19 in

the outer corner piece 17 might be more accurately described as being rabbets, since they are only one sided so that the outermost side of each rib in the row connected to each corner strip and corner piece will be flush with the outer ends thereof.

10 The adjoining ends of portions 12, 13 of rib 6 are preferably glued in the grooves in strip 15 and in piece 17, and the opposite ends of the ribs 6 are preferably glued in grooves 9, 10 respectively formed in ridge piece 1 and base member 8.

Any number of ribs may be secured in a row in each panel 2 dependent upon the spacing of the ribs and the length of the ridge and base pieces, and the corner elements 15, 17 being preferably of the same length. As an example, for ribs in which the leg portions are about 7½ feet long and the roof portions are about the same length, there may be four ribs to each panel 2. These, if of wood, may be about three-quarters of an inch thick. The leg and roof portion of each rib may taper in width from about 4½ inches at their adjoining ends to about 2½ inches at their outer ends. The ribs are arranged with the flat sides of adjacent pairs in opposed, parallel relationship and with their inner and outer edges in coplanar relationship. The designation "inner" edges refers to the edges that are on the inside of the corner formed by the portions 12, 13 whereas the "outer" edges are those on the outside of such corner. Furthermore, when the building is constructed, as will be later described, the outside edges of the ribs will support the outer side of each panel 2 that is outwardly relative to the inside of the room or building, whereas the inner side of each said panel will face into the room, the side walls of which are defined by part of each panel 2.

20 The outer edges of the ribs 6 are covered by relatively rigid sheets 24, 25, the sheet 24 covering the outer edges of roof portions 13 of said legs, whereas sheet 25 covers the outer edges of leg portions 12. The sheets 24, 25 are preferably glued to the ribs and to each other along their adjacent edges at the outer corner of the outer corner piece 17, and are likewise glued along their adjacent edges to said corner piece.

25 The inner edges of ribs 6 are covered by relatively rigid sheets 26, 27 that are glued to said ribs, and these sheets may be halves of the same sheet that is steamed for bending across the concave side 20 of inner corner piece 15, and that is glued to said concave side. Sheet 26 covers the underside of roof section 4 while sheet 27 covers the inner side of side wall section 5.

30 The core ribs 6 may be apertured at 28 for ventilation, except the end rib of the panel that is to be at either end wall of the building, which latter rib is preferably imperforate, as seen in Fig. 2, the said panel in Fig. 2 being one of the end panels shown in Fig. 1 as next to the end wall 60 of the building. The adjoining ribs in adjacent pairs of panels have their apertures 28 in registration with each other. Cross pieces 29 (Fig. 2) may be provided between the adjacent pairs of ribs in each panel 2 for supporting the sheets 24 to 27 and to which said sheets are secured. These cross pieces may also be apertured as at 30.

35 From the foregoing, it is seen that when the side wall section 5 of the panel 2 is vertical, the roof section 4 of said panel will extend slantingly upwardly, and inner sheets 26, 27 will be under compressive stress while outer sheets 24, 25 will be under opposite strain. This assumes no support for the panel at the ridge piece. However, when a pair of said panels 2 are positioned 75 with their side wall sections vertical and with

their ridge pieces together as in Fig. 1, the tendency is for the lower ends of the side wall sections to be forced apart. Suitable means, later described, prevents this, but these forces that still exist are taken by the covering sheets 24 to 27 rather than by the core ribs. In a panel having core ribs of the size hereinbefore mentioned, the covering sheets may be of about $\frac{1}{8}$ inch plywood. This structure makes it possible to provide any suitable and desired apertures in the core ribs and cross pieces without weakening the structure. The sheets 24, 26 are, of course, glued to the ridge piece 7, as well as to the inner corner piece 15, and the sheets 25, 27 are glued to the base member 8 and parts rigid therewith, as well as to the outer corner piece 17.

This base member 8 is rabbeted at 35 along its inner edge to receive the lower edge of sheet 2. Across the outer edge of member 8 is glued a strip 36 extending longitudinally of said member, and which strip depends an appreciable distance below member 8 for covering the edge of the floor panel, and for providing a stop and locking means, as will later be described. This strip 36 may be considered as integral with base member 8 and is part of said base member, and is recessed on its outer side for receiving the outer sheet 26 of the panel 2 and for covering the end grain of said sheet as best seen in Fig. 8. On its inner side the depending portion of strip 36 carries a rib 37 extending longitudinally of said strip that coacts with the floor structure for automatically locking each panel 2 to the floor as will later be described.

The underside of base member 8 of each panel 2 is formed along its inner edge nearest sheet 27 with a downwardly projecting ridge 38, the edges of which are rounded in cross-sectional contour. Thus a groove or channel 39 (Fig. 14) is formed between ridge 38 and strip 36 that opens downwardly and in which groove is adapted to fit a ridge on the floor panel about the longitudinal axis of which the panel 2 is adapted to swing in erecting the building.

The core ribs 6 may or may not be apertured which may also be the case with the ridge pieces 7. The latter may be provided with registering openings 40 where through ventilation is desired from the panels at opposite sides of the building. Whether or not the ribs or ridge pieces are apertured, the construction described above is ideal for holding insulation material 41 between the sheets 24, 25, and 25, 27 that form the opposite side walls of each panel 2. This insulation material may be any standard fibrous material, such as rock wool, etc., that may also constitute sound proofing, in which latter case the sheets 26, 27 may be perforated as indicated in Figs. 13, 16, 17 at 42.

The ridge piece 7 of each panel 6 is centrally formed with a groove extending longitudinally thereof on its side that faces outwardly of the ends of the ribs 6. A strip 43 is secured by glue or the like, in about one-half of the length of each ridge piece. The other half of each groove is open. As half the thickness of each strip 43 projects from the groove in which it is secured, and as the projecting half is formed to fit in the open half 44 of the groove that is in the ridge piece opposite thereto (Figs. 18, 19), it is seen that when the ridge pieces are together the strip 43 in one ridge piece of the panel at one side of the building will be in axial alignment with the half that is in the ridge piece opposed thereto. Thus the ridge pieces will be axially

aligned by the fitting together of the complementary formed strips 43 and grooves 44.

The portions 12, 13 of each of the end core ribs 6 in each panel 2 are each provided with an angle strip generally designated 45, and also ridge piece 7 is provided with a similar strip 45. The leg 45 of each strip 45 is secured to each portion 12, 13 and to piece 7, while the head 47 of each strip extends angularly over the rib or piece adjacent thereto (Figs. 10, 11). The sheets 24, 25 may be cut away along the adjacent edges of adjacent pairs of panels 2, and along ridge piece 7 so as to permit the heads 47 of the angle strips to project over the ribs and piece 7 without projecting outwardly of the outer surfaces of sheets. Thus when two ridge pieces 7 are together in side by side relationship, which pieces are on the panels opposite each other at opposite sides of the building, a groove will be formed down the ridge, and on both the upper and under sides inasmuch as the sheets 26 are cut away along the ridge pieces 7 the same as for sheets 25. In these grooves (above and below the ridge pieces) project the heads of angle strips 45. Along the adjoining end ribs of each adjacent pair of panels along the outer edges of the ribs is a similar groove into which projects the heads of the angle strips secured to said ribs.

A channel strip 48 having interned edges 49 along its sides may be slipped longitudinally of each adjacent pair of angle strips so that heads 47 of the latter will be held in each channel. The edge portions 49 will prevent the withdrawal of the strips 45 laterally from the channel in which heads 47 are positioned.

The strips 48 that connect the angle strips that are secured to the ridge pieces 7 may extend the full length of the building, thus aligning the ridge pieces axially, while the strips 48 that connect adjacent leg portions 13 terminate adjacent the upper and lower ends of said pieces. The strips 48 that connect adjacent roof portions 13 extend from the ridge pieces 7 to the strips 48 that connect the leg portions, and the webs 45 of such latter strips may be extended and bent downwardly, as at 49 (Figs. 7, 20) so as to extend over the upper open ends of the strips 48 that connect the leg portions 12.

The sheets 21 of adjacent pairs of panels 2 and sheets 26 are not necessarily cut away along their adjacent edges. Instead, the leg and roof portions 12, 13 of the end ribs may be grooved or rabbeted as at 50 for receiving in such grooves the ends 51 of spring legs 52 that are extended from opposite edges of closure strips 53 (Fig. 10). The legs 52 are merely brought together against their tendency to be sprung urged apart, and are then slipped transversely past the adjacent edges of adjacent pairs of sheets 26, 27 of the adjacent panels 2. Ends 51 then enter oppositely opening grooves 50 and the divergence of the legs 52 upon being released causes the strips 53 to be tightened against the panels.

Thus the strips 48 are connecting strips whereas strips 53 are merely crack closing strips. The fact that the angle strips on the panels 2 are relatively movable enables automatic adjustment of the adjacent panels due to slight variations between them upon sliding the connecting channel strip 48 into position connecting said angle strips. The latter are preferably continuous, but need not be so in all instances. However, the sliding of the connecting channel in place is facilitated where said angle strips are

continuous rather than where they are merely spaced clips.

The adjacent edges of the roof sections of the panels correspond with that of the side wall sections, and closure strips identical with the strips 53 of the side wall sections close the cracks along the adjoining panels on the undersides of the roof sections.

In Figs. 5, 6, a slight modification in the corner construction of the panels 2 is illustrated. The same members are employed where the structure is identical with that of Figs. 2 to 4.

In the modified form, an inner corner piece 55 is provided that has a concave inner surface 56 the same as for strip 15, but this strip is rabbeted at 57 along the side edges of the curved portion, and the edges of the inner covering sheets 58, 59 that respectively correspond with sheets 26, 27 terminate at their adjacent edges in said rabbets (Fig. 5), whereas in the form shown in Fig. 2 the sheets 26, 27 are continuous across the inner side of the inner corner strip. This structure may be adopted where it is not feasible to steam and bend inner covering sheets of the panels 2.

Also in Fig. 5 the outer roof covering sheet 60 is extended to provide an outwardly projecting eave 61, and an eave strip 62 is provided below said eave. Glue is preferably used in all instances for securing the covering sheets to the corner strips or pieces and to the core.

It is obvious, of course, that the outer covering sheets of each panel may be continuous and that the outer corner piece may be convexly curved on its outer side for defining a curve over which such outer sheet could be bent after steaming. However, in the claims where the terms "integral" or "integrally" are used with respect to the coverings for the panels 2, it is intended to refer to inseparable structure such as would be provided for by gluing pieces together, thereby making them virtually one piece.

Floor panels

The floor panels 1 may each be of the same width as the width of the panels 2 (Fig. 1) and panels 1 may be of a length to extend from side to side of the building or they may be in sections.

In any event, said floor panels comprise parallel, spaced core ribs 65 fitted at their ends in transverse, spaced grooves 66 in end pieces 67 (Fig. 15). The end grooves in pieces 67 are virtually rabbets the same as were provided in ridge pieces 7 for ribs 6.

An upper covering sheet 68 as of plywood or any other suitable relatively rigid material, covers one side of the core frame that is formed of ribs 65 and end pieces 67, and is glued to the said ribs and end pieces, while a similar sheet 69 is glued to the opposite side of the frame. Between sheets 68, 69 may be heat insulation material 71, if desired, and the ribs may be apertured, as at 70, to provide through ventilation, if desired.

Angle strips generally designated 72 (Fig. 9) identical with the angle strips on adjacent edges of adjacent panels 2 are provided on the two opposite edges of each panel 1 that is intended to be next to similar panels, said strips bearing the same numbers as those on panels 2, while connecting channels generally designated 73 are identical with the channel strips 48. In the case of the floor panels, the angle strips 72 may be adjacent both sides of the panels for connection by channel strips 73 at both sides, thus eliminat-

ing covering strips 53 such as are shown in Fig. 10.

The end pieces 67 of the floor panels may each be formed on their outer sides with a groove 74 that extends longitudinally thereof, and which groove is adapted to receive therein one of the strips 37 provided on the inner side of each strip 36 that is integral or glued to each base member 8 on each side wall section 5 of each panel 2. Cross members parallel with end pieces 67 may be secured at spaced intervals between ribs 65, and any suitable floor girders 75 on foundation elements 76 which may support the floor panels in horizontal position.

Secured to the floor panels over each of the end pieces 67 is a strip 76 (Figs. 8, 15) that is adapted to pivotally fit in the groove 39 below each member 8 on the panels 2, so that the panels 2 can be swung from dot-dash positions 2' (Fig. 1) to the full line positions with ridge pieces 7 together.

End panels

The end panels 3 are of similar cross-sectional contour around all of the outer edges where the latter extend along the floor, side wall, and roof that are formed by panels 1, 2. Where, as in Fig. 1, two end panels are provided for each end of the building, these are connected along their adjacent sides in identically the same manner as adjacent panels 2 along one side or the other of the building are connected.

Each end panel comprises a core frame having a base member 80 (Fig. 15) and a head member 81 (Fig. 17) and a vertical side member 82 (Fig. 16), the latter extending between one of the corresponding ends of the base and head members. Parallel with each of these members and along one side thereof is a strip 84 that extends outwardly (relative to the center of the panel) in the same manner that strip 36 on each panel 2 extends outwardly of the main body of the latter. Thus the outer surface of each member 80 to 82 inclusive, and the side of each strip 84 adjacent thereto provides a right angle contour like a rabbet, whereby each of said members provides a ledge for respectively being positioned to overlie the marginal portion of the floor panel 1, and the roof section 4 and side wall section 5 of one of the end panels 2, while the strips 84 extend over the edges of said floor panel and said roof and side wall sections in the same manner as strips 36 extend over the edges of the floor panels.

The strips 84 are recessed on their outer sides to receive the marginal portions along three of the edges of the outer covering sheet 85 of the end panel, while the members 80 to 82 inclusive, are respectively rabbeted for receiving the corresponding edges of an inner covering sheet 86. These sheets or coverings may be of any relatively rigid material, such as plywood, and said sheets are glued to the members 80 to 82 and to strips 84, and strips 84 are respectively glued to the particular member that is adjacent each such strip.

Ribs 85 parallel with the side member 82 extend between the base and head members 80, 81, the latter being preferably grooved to receive the ends of said ribs, and where two or more panels are used to complete one end of the building, as in Fig. 1, an end rib identical with any rib 85 is at the adjacent edges of each adjacent pair of said panels, and such adjacent ribs respectively, carry angle strips identical with the strips of Fig. 75 10 that are connected with a channel strip iden-

tical with channel strip 48. Closure strips 52 (Fig. 1) identical with the strips 52 that cover the cracks between panels 2 inside the building are provided for panels 3. The structure of adjacent edges of an adjacent pair of end channels is not shown since it would be identical with the structure shown in Fig. 10.

The structure shown in detail in Fig. 12 is identical for that along the floor panel or roof section of the panel 2, and the means for connecting the side wall section of panel 2, as shown in Fig. 12, with the end panel 3 is identical with the means for connecting the roof section of panel 3 with the end panel, or for connecting the end panel 3 with the floor panel.

This connecting means, as shown in Fig. 12, comprises angle strips, generally designated 90, that are identical with the angle strips 72 of Fig. 9. One of said angle strips is the strip 45 that is secured to the end rib 6 of each end panel 2 and the strip that is secured to the end rib 65 of each end floor panel 1. The other strips are carried by each end panel 3 and are respectively secured to each strip 84 and when each end panel 3 is slipped into place, the strips on the panels 1, 2 will be opposed to the strips on the panel 3.

The outer edges of strips 84 are rabbeted to receive the connecting channel strips generally designated 91 (Fig. 12) and the outer panel-covering sheets 24, 25, 69 are cut away along the end ribs that are adjacent panel 3 whereby the channel strips 91 can readily engage the legs of the angle strips 90 in the same manner as has already been described with respect to the adjacent panels 2, or floor panels 1.

If desired, a strip 94 may be secured to each panel 3 along its upper edge (Fig. 17).

The inner sheets 86 of the end panels may be perforated as indicated at 42 (Figs. 16, 17) for sound proofing structure if desired, and an insulation material 95 (Fig. 16) may be held between the sheets 85, 86 either for sound proofing or for heat insulation, or for both.

Erection of building

In operation, the floor panels 1 may first be positioned on girders 75 and connected together by strips 13 after which one or both rows of panels 2 may be positioned on the floor with the groove 39 below each base member over the strip 17 on the floor panel (Fig. 8). After it is optional if the operator shall connect the adjacent panels of each row by strips 48, or if each pair of opposite panels 2 at opposite sides of the floor shall be swung about strips 17 to meeting relation of ridge pieces 7. In most instances several adjacent panels along the opposite sides of the building are connected by strips 48 before erection, thus providing a group of a similar number of panels at opposite sides of the building that can be swung from positions 2' (Fig. 1) to full line positions as units.

In swinging the panels 2 upwardly along the lines indicated by the arrows (Fig. 19) it will be seen that the ribs 37 on strips 36 will automatically swing into the recesses or grooves 74 in end pieces 67 of floor panels 1. There is enough spring in the panels 2 to permit the ridge pieces 7 to clear each other in being moved to meeting relation with the aligning strips 43 (Figs. 18, 19) in the grooves 44. Thus even one workman can swing one or several panels 2 along one side of a building to the desired position with the side wall sections 5 vertical, and then prop such panels up while he swings the panels at the op-

posite side of the building into place and connects the ridge pieces.

After the panels 2 along opposite sides of the building are up, one or more connecting channel strips 48 may be slipped over the legs of the angle strips that are respectively carried by the ridge pieces, and any disconnected pairs of adjacent panels can be similarly connected by such channel strips. Conventional non-drying mastic can be used wherever it is thought desirable to insure against possible leakage at any joint or splice.

After the panels 2 are in place, as above described, the end panels may be positioned in the open ends of the building and connected to the end panels 2 by the channel strips 94 (Fig. 12) that extend along both the roof sections 4 and the side wall sections 5 of said end panel. Windows and doors may be provided on or in the desired panels, which is not part of the invention herein disclosed.

It will be seen from the foregoing description that the end wall panels are telescopically fitted in the ends of the building, and the strips 84 cover the end edges of the outer sheet 85 of each end panel as well as covering the end edges of the panels 2 and of the floor panels 1. Also the strips 36 on the panels 2 cover the end edges of sheets 25 and the edges of the floor panels 1 (Fig. 8).

Each panel that goes into making up the roof side walls, end walls and floor of the building is a double walled panel that in itself forms an inner and outer wall, either or both of which may be left as they are or painted or covered with any desired covering material should the builder wish to do so. Where insulation material is between the inner and outer sheets of each panel, the same is held by the sheets and ribs in each panel for handling of the panels in exactly the same manner as though the panels were merely insulated by the air space between the covering sheets. Furthermore, such space in each panel provides for concealing of wires, pipes, heaters, etc. One of the most desirable characteristics of each panel is its lightness and extreme rigidity and their manner of fabrication makes their production cheap and accurate.

While wood is shown as the main material used, it is obvious that metal may be employed for certain parts, such as the ribs or covering sheets, or both, with suitable means for securing them together, such as welding where metal to metal connections are made. The use of plywood for the covering sheets and of wood for the core frames of the panels has been found to be highly satisfactory, and where difficulty in obtaining proper plywood for the outside sheets has been encountered, the ordinary plywood covered with roofing paper or composition sheet material can be used.

Having described my invention, I claim:

1. In a prefabricated building, a floor, a pair of separable rigid panels of similar shape and size each comprising a roof section and a side wall section integrally secured together and extending at an angle to each other with the outer edges of said roof sections that are remote from said side wall sections in meeting relation over said floor and with the said side wall sections supported in substantially vertical spaced opposed relation on said floor along two opposite edges of the latter, the side wall section and roof section of each panel being part of the roof and part of the opposite side walls respectively of such building, complementarily formed elements respectively secured to said floor along each of said opposite edges thereof and to the lower edges of said side

wall sections providing a weather and insect seal between said floor and said lower edges and pivotally supporting the latter for swinging from positions slantingly extending over said floor with said meeting edges of said roof sections disengaged, to said vertical positions with said edges of said roof sections in said meeting relation, and means for securing said roof sections in said meeting relationship.

2. In a prefabricated building, a floor, a pair of separable rigid panels of similar shape and size each comprising a roof section and a side wall section integrally secured together and extending at an angle to each other with the outer edges of said roof sections that are remote from said side wall sections in meeting relation over said floor and with the said side wall sections supported in substantially vertical spaced opposed relation on said floor along two opposite edges of the latter, the side wall section and roof section of each panel being part of the roof and part of the opposite side walls respectively of such building, complementarily formed elements respectively secured to said floor along each of said opposite edges thereof and to the lower edges of said side wall sections providing a weather and insect seal between said floor and said lower edges and pivotally supporting the latter for swinging from positions slantingly extending over said floor with said meeting edges of said roof sections disengaged, to said vertical positions with said edges of said roof sections in said meeting relation, and means for securing said roof sections in said meeting relationship, and means on said side wall sections extending over the said edges of said floor.

3. In a prefabricated building, a panel comprising a roof section and a side wall section extending angularly relative to each other and secured together for handling as a unit in erecting the building, a floor panel, a strip secured on said floor panel along one of its edges in engagement with the lower edge of said side wall section for securing said side wall section against lateral shifting on said floor panel, an extension on said side wall section projecting downwardly therefrom across the edge of said floor panel adjacent said side wall section, and means on said extension in interlocking engagement with said floor panel for securing said side wall section to said floor panel against vertical movement of said section away from said floor panel said means being rigid with said extension and releasable from said floor panel upon swinging the upper end of said side wall section inwardly about its lower edge to a position extending over said floor panel.

4. In a prefabricated building of the character described, a pair of horizontal rows of separable rigid panels, the panels of said rows being supported at one of their edges on said floor along two opposite edges of the latter with their opposite edges in substantially abutting relation centrally above said floor, separate ridge pieces respectively secured to each of said panels at their said opposite edges, the ridge pieces on the panels of one of said rows being horizontal and in axial alignment and the ridge pieces on the panels of the other row also being in axial alignment and parallel with the ridge pieces of the first mentioned row and in engagement with the latter pieces, means for securing the ridge pieces on adjacent panels in each row and on the panels in opposite rows of said pair together, means pivotally supporting said panels on said floor and for swinging of said panels of said pair of rows to positions with the said ridge pieces on one row

in engagement with the ridge pieces on the other row.

5. In a prefabricated building of the character described a pair of panels each formed with a vertically extending side wall section and a roof section integral therewith extending slantingly upwardly from the upper end of the side wall section, the uppermost edges of said roof sections being substantially in meeting relationship and the side wall sections being in opposed relationship, a single rectangular floor panel extending between the lower edges of said side wall sections and supporting said pair of panels thereon, said floor panel including means rigid therewith for engaging the lower ends of said side wall sections to hold said lower ends on said floor panel against the tendency of said lower ends to move away from each other whereby said floor panel functions as a combined tie rod and support for the lower ends of said side wall sections.

6. In a prefabricated building of the character described a pair of panels each formed with a vertically extending side wall section and a roof section integral therewith extending slantingly upwardly from the upper end of the side wall section, the uppermost edges of said roof sections being substantially in meeting relationship and the side wall sections being in opposed relationship, a single rectangular floor panel extending between the lower edges of said side wall sections and supporting said pair of panels thereon, said floor panel including means rigid therewith for engaging the lower ends of said side wall sections to hold said lower ends on said floor panel against the tendency of said lower ends to move away from each other whereby said floor panel functions as a combined tie rod and support for the lower ends of said side wall sections, the free opposite lateral edges of the panels of said pair and two of the opposite edges of said floor panel terminating in a pair of parallel vertical planes to enable the positioning of a similar set of panels along either of said edges for forming a continuation of said floor panel coplanar therewith and a continuation of the side wall and roof sections of said pair of panels respectively coplanar with each of said sections.

7. A prefabricated building comprising a plurality of corresponding segments arranged in a row, each of said segments comprising a pair of panels, each panel being formed with a vertically extending side wall section and a roof section integral therewith extending slantingly upwardly from the upper end of the side wall section and each segment further comprising a single floor panel on which the lower ends of the side wall sections of said pair of panels are supported, means rigid on the floor panel of each segment engaging the lower ends of the pair of panels supported thereon for holding said lower ends against movement apart whereby said floor panels function as a combined support and tie rod for the panels supported thereon, the free lateral adjacent edges of the panels of each segment being substantially in meeting engagement and means along said edges for removably securing the panels of said segments together.

8. In a prefabricated building, a panel comprising a generally horizontally extending roof section and a vertically extending side wall section rigidly secured together for handling as a unit in erecting a building, a floor, a strip separate from said side wall section secured on top of said floor along one of the edges of the latter, the lower edge of said side wall section being formed with a

downwardly opening channel receiving said strip therein for swinging of said side wall section about said strip from a position extending over said floor with the said roof section engaging said floor to a position with said side wall section extending vertically, one side of said channel extending downwardly and across the edges of said floor adjacent thereto.

9. In a prefabricated building, a panel comprising a flat horizontally extending roof section and a flat vertically extending side wall section rigidly secured together for handling as a unit in erecting the building, a floor, means secured to said floor along one of its edges in pivotal engagement with the lowermost edge of said side wall section for swinging of said side wall section thereabout from an inclined position of said side wall section to its vertically extending position, said side wall section being free from securing to said means for removal from the latter when said side wall section is in said inclined position, and means respectively connected with said side wall section and said floor automatically movable into interlocking relationship for locking said side wall section to said floor section against vertical movement of said side wall section from said floor upon movement of said side wall panel to said vertical position.

10. In a prefabricated building, a floor, a pair of separable rigid panels of similar shape and size each comprising a roof section and a side wall section integrally secured together and extending at an angle to each other with the outer edges of said roof sections in meeting relation over said floor and with said side wall sections supported in substantially vertical spaced opposed relation on said floor, the side wall section and roof section of each panel being part of the roof and part of a side wall of such building, a downwardly opening channel strip extending longitudinally of the meeting edges of said roof section open at one of its ends and having its transverse width extending transversely across said meeting

edges, separate means respectively rigid with each roof section extending into the open side of said channel strip and slidably into said channel strip through the open end of the latter, said strip being formed with elements rigid therewith holding said separate means within said channel strip holding said separate means within said channel strip against movement thereof through said open side of said strip, said elements being slidably longitudinally of said strip whereby said panels may be moved relatively longitudinally of said strip.

ERNEST J. KUMP, JR.
